UNITED STATES PATENT OFFICE.

BLUFORD W. BROCKETT, OF CLEVELAND, OHIO.

COOLING-SYSTEM CONTROL.

1,328,815.

Specification of Letters Patent. Patented Jan. 27, 1920.

Application filed March 8, 1917. Serial No. 153,449.

To all whom it may concern:

Be it known that I, BLUFORD W. BROCKETT, citizen of the United States, residing at Cleveland, in the county of Cuyahoga and 5 State of Ohio, have invented certain new and useful Improvements in Cooling-System Controls, of which the following is a specification.

This invention relates to cooling systems 10 for internal combustion engines, and more particularly to such engines when used on motor vehicles.

The object of the invention is to provide an improved system of this kind which can 15 be applied to any automobile engine at low cost, which is capable of delicate regulation, and which preferably employs electrical energy for producing variation in the cooling effect upon the engine. A further object of 20 the invention is to provide a system of this kind including a thermostat or heat responsive device whose energy is utilized to make and break an electrical circuit for producing a variation in the cooling effect, and which 25 thermostat may include, as one of its members, the water manifold commonly employed for conducting heated water from the engine to the radiator. A further object of the invention is to utilize for the production 30 of electric energy a circuit which is closed only while the engine is running, whereby, upon stopping of the engine, said circuit is broken, with the inevitable result of promptly closing a shutter to restrict the circulation 35 of air through the radiator and thereby protect said radiator.

Further objects of the invention are in part obvious and in part will appear more in detail hereinafter.

40 The invention comprises the construction and arrangement of parts hereinafter described and claimed.

In the drawings, which represent one embodiment of the invention, Figure 1 is a 45 side elevation, partly broken out and in section, illustrating the invention applied to an internal combustion engine; Fig. 2 is a detail longitudinal section, illustrating a portion of the thermostat and the electrical 50 contact devices controlled thereby; Fig. 3 is a detailed section of the electrical motor means for actuating the shutter; Fig. 4 is a detail elevation, on a larger scale, of a portion of the thermostat; and Fig. 5 is a 55 diagrammatic view of the electrical circuits.

Referring to the drawings, 1 indicates a

suitable internal combustion engine, which may be of any type or construction, and as illustrated is a six cylinder engine of common form. Said engine is provided with 60 the usual water jacket, the cavities or spaces in which communicate through branch pipes 2 with a water manifold 4, preferably made of copper, brass, or some other material expandible by heat, and which manifold conducts the water heated by the engine to the upper portion of the radiator 5, from which the cool water returns to the engine water jacket by way of pipe 6 as is usual.

65 Suitable means is provided for varying the cooling effect upon the circulating water by the radiator, so as to substantially maintain the water or other liquid in the engine jacket at uniform temperature. This result may be secured by by-passing a portion of 70 the water around the radiator when the temperature of the water is low, or otherwise varying the water circulation, as is well known and common in the art, the variation in the water circulation being controlled by 75 a valve. Preferably, however, the variation in the cooling effect is produced by the provision of means for more or less interrupting the flow of air through or past the radiator. The means shown comprises a shutter or 80 screen, similar to a hot air furnace radiator, and comprising a series of vanes or wings 7, pivoted at 8 to a stationary frame and having arms 9 pivotally connected to a vertically moving rod or bar 10. As said bar or 85 rod is elevated or depressed the vanes open or close. When the shutter is closed the circulation of air through the radiator is cut off so that there is practically no cooling effect, but as said shutter opens the cooling 90 effect is more or less increased to a maximum.

95 Said shutter is actuated by electric motor means, which may be of any suitable form and as illustrated comprises an electromagnet or solenoid 11, whose coils are in a circuit to be described. Said solenoid, when energized, attracts the core 12 attached to a rod 13 connected by a link 14 to one arm of a lever 15 pivoted at 16 to the frame, and whose other arm 17 is connected to the 100 rod or bar 10. A tension spring 18 connected to lever arm 15 and to a fixed point normally tends to close the shutter. The movement of the solenoid core is preferably steadied or regulated by suitable dash pit 105 for which purpose said core is connected 110 to a rod 19 to a doubled faced piston 20

traveling in a cylinder 21. The chambers on opposite faces of the piston communicate by a by-pass channel 22, which may be more or less restricted to vary the dash pit effect 5 by a regulating valve 23.

As will appear hereinafter, the circuit to the coils of solenoid 11 is always broken when the engine is in a state of rest. Consequently when the engine is not running 10 the position of the parts is as indicated in Figs. 1 and 3, the core 12 being held away from the solenoid by the tension of spring 18, which spring also closes the shutter, as a result of which the radiator is always 15 protected when the engine is in a state of rest.

Fig. 5 illustrates the electric circuit for controlling the supply of current to the solenoid coil 11. As is usual, the circuits 20 are all grounded upon the metal body of the automobile. 24 indicates the generator, which, as usual, is coupled to be driven by the engine. Said generator is in a circuit 25 passing through the point 26 to the combination switch 27, thence through wire 28 and ammeter 29 to the storage battery 30, for charging said battery. The movable member of the combination switch 27 is pulled out when the engine is started, and 30 not only connects the shutter to the storage battery, but also completes a circuit to the wire 31 leading to the ignition coil. The circuit for the coil 11 of the solenoid is connected to the point 26 of the battery charging circuit, and passes from said coil through the switch contacts 32 and 33 to the ground. The making and breaking of the solenoid circuit is controlled by a thermostat which actuates or controls the contacts 32 and 33, in a manner to be described. It will be apparent that no current can flow through the solenoid 11, either from the generator or from the storage battery, unless the switch 27 is closed. This switch is 40 always closed by the driver before starting the engine and is opened whenever the engine is stopped to avoid loss of current through the ignition system. Consequently the solenoid coil is always deenergized when 45 the engine is stopped, thereby allowing the spring 18 to promptly close the shutter.

Any suitable thermostat may be provided for controlling the electrical contacts 32, 33. Said thermostat may be sensitive to variations 50 in the temperature of the cooling water, by exposing the expansible member of the thermostat to the cooling water, or may be made sensitive to variations in the temperature of the engine itself, or of the air within the engine hood or casing. The drawings illustrate one suitable construction 55 for this purpose. As illustrated the thermostat comprises two members, one of which is the water manifold 4 which is made of material expansible by heat and therefore

contracts and expands with variations in the temperature of the cooling water. Said member cooperates with an expansible member, shown as a pencil or rod 34, which may be made of carbon or any other incompressible material. Said rod at one end engages an abutment 35 fixed to the engine manifold and at its other end abuts one end of a rod 36 passing through an opening in a bridge wall 37 of a casing 38 screwed to a boss 39 carried by the engine manifold. The carbon pencil may be protected against injury by a suitable jacket 40. Rod 36, on one side of the wall 37, is provided with a collar 41 forming an abutment for the compression spring 42 held in place by a casing cap 43. The length of said rod may be regulated by turning the milled head 33, which has threaded connection with a portion of said rod. This head forms one of the contacts 85 of the solenoid controlling switch before referred to, and by its contact with other metallic parts of the apparatus provides connection of said switch to ground. It operates with the spring contact 32 attached 90 to a binding post 44 to which the lead wire from the solenoid coil may be connected.

With the arrangement described, when the temperature of the cooling water or the space within the hood 45 is low the engine manifold 4 contracts and pushes the carbon pencil 34 to the right in Fig. 2, against the pressure of spring 42, consequently breaking the electrical connections between the contacts 32 and 33. The circuit to the solenoid 100 is therefore broken and the shutter is held closed by a spring 18. This is always the condition when the engine is cold. When the engine warms up and the temperature of the cooling water rises to or slightly 105 above a critical temperature, the manifold 4 expands longitudinally, allowing the spring 42 to move the carbon pencil, rod 36 and contact 33 to the left in Fig. 3, thereby closing a circuit through the solenoid at the 110 contacts 32, 33, and energizing said solenoid, which moves over the core 12 and opens the shutter. A cooling effect will therefore be produced by a flow of air through the radiator, said effect continuing until the temperature of the cooling water has fallen below the critical point, when the manifold 4 will have contracted and again broken the circuit. 115

One particular advantage of this construction is the prompt closing of the shutter whenever the engine is stopped, due to the fact that the switch 27 is then opened. Consequently, irrespective of whether the solenoid circuit is closed or open through contacts 32, 33, the flow of energy to the solenoid 11 ceases, and the spring 18 closes the shutter. 120

It will, of course, be understood that the invention is not limited to the particular 130

construction illustrated, but is capable of considerable modification within the scope of the appended claims without departing from the spirit of the invention.

5 Having described my invention, I claim:—

1. The combination of an internal combustion motor, a cooling system therefor including a radiator, means for interrupting the flow of air to said radiator, a source of 10 electrical energy connected to a circuit when the motor is running, motor means under the control of said circuit for operating said interrupting means, and a device responsive to heat conditions of the motor for controlling said circuit.

15 2. The combination of an internal combustion motor, a cooling system therefor including a radiator, means for interrupting the flow of air to said radiator, a source of 20 electric energy connected to a circuit only when the engine is running, motor means under the control of said circuit for operating said interrupting means, and a device responsive to the heat condition of the engine for opening and closing said circuit.

25 3. The combination of an internal combustion motor, a cooling system therefor including a radiator, means for interrupting the flow of air to said radiator, a source of 30 electric energy connected to a circuit only when the engine is running, means normally tending to operate the interrupting means to prevent the flow of air to the radiator, motor means under the control of said circuit for 35 operating said interrupting means, and a device responsive to the heat condition of the motor for controlling said circuit.

4. The combination of an internal com-

bustion motor, a cooling system therefor including a radiator, a shutter for interrupting the flow of air to said radiator, means normally tending to close said shutter, electrically operated motor means for opening said shutter, a circuit connected with a source of electric energy only when the engine is running, said circuit being connected to the electrical motor means for actuating the shutter, and means responsive to heat condition for controlling said circuit.

40 5. The combination of an internal combustion motor, a cooling system therefor including a radiator, a shutter for interrupting the flow of air to said radiator, means normally tending to close said shutter, electrically operated motor means for opening 45 said shutter, a circuit connected with a source of electric energy only when the engine is running, said circuit being connected to the electrical motor means for actuating the shutter, and a thermally controlled contact device for controlling said circuit.

50 6. The combination of an internal combustion motor, a cooling system therefor including a radiator, a shutter for interrupting the flow of air to said radiator, and a 55 thermostatic device for controlling said shutter and comprising a water manifold for said motor having movement responsive to heat conditions of the motor, and another element outside of the water manifold adapted to be affected thereby for producing movement to control the operation of said shutter.

60 In testimony whereof I affix my signature.

BLUFORD W. BROCKETT.
